UNITED STATES PATENT OFFICE.

PERCY STERNAU, OF LOUISVILLE, KENTUCKY, ASSIGNOR OF ONE-HALF
TO GEORGE H. BROOKS, OF LOUISVILLE, KENTUCKY.

STAMP-HOLDING BOX.

No. 830,188.

Specification of Letters Patent.

Patented Sept. 4, 1906.

Application filed August 24, 1905. Serial No. 275,612.

To all whom it may concern:

Be it known that I, PERCY STERNAU, a citizen of the United States, residing at Louisville, in the county of Jefferson and State of Kentucky, have invented a new and useful Stamp-Holding Box, of which the following is a specification.

This invention relates to means for holding printing-stamps and the like.

10 The principal object is to provide a box or holder wherein the stamps will be supported directly on the inking-pad, will thus be kept moistened and soft, and will be ready for immediate application to the articles to be stamped upon the removal of said stamps from the box or holder.

Two embodiments of the invention are disclosed in this application; but an inspection of the appended claims will make it clear 20 that said invention is not limited solely to the structures set forth.

In the drawings, Figure 1 is a perspective view of an embodiment of the invention that is at present considered preferable. Fig. 2 is 25 a longitudinal sectional view therethrough with the cover closed. Fig. 3 is a cross-sectional view showing the tray removed. Fig. 4 is a cross-sectional view of a slightly-modified form of construction.

30 Similar reference-numerals designate corresponding parts in all the figures of the drawings.

In the embodiment illustrated in the first three figures a stamp-holding box is employed, comprising a rectangular body 5, having a bottom 6 and a cover 7, preferably hinged thereto, as shown at 8, and having means—as, for instance, a hook and eye 9 and 10—for securing the cover in closed position upon the body.

40 Located in the lower portion of the body and preferably detachable therefrom is an inking-pad 11, which may be of any desirable absorbent material, said pad being located on a base 12, that rests upon the bottom 6. A tray is detachably fitted within the body 5 and consists of side walls 13 and longitudinally-disposed partitions 14, said partitions thus dividing the interior of the body into a plurality of stamp-receiving compartments. This tray may be provided with a bottom 15, of fabric or other material permeable to the ink, said bottom being secured to the side walls by strips 16 and constitut-

ing, in effect, the top of the pad. If desired, 55 this bottom may be dispensed with entirely.

From the above it will be apparent that stamps or stencils, as 17, placed in the compartments between the partitions, will rest upon the pad, will therefore be kept in moistened and soft condition, and when said stamps or stencils are removed from the box they will be in condition for immediate use. This structure therefore constitutes a labor-saving device, as it eliminates the necessity 60 of detaching the stamps from the holders and applying the same to a pad before they can be used. To reink the pad, it is only necessary to remove the tray, whereupon the bottom 15 will support the stamps in the box, 70 so that all will be carried by the tray, leaving the body of the pad exposed. There is therefore a distinct advantage in the employment of the bottom 15; but, as already stated, the bottom may be dispensed with, in which case 75 the stamps must be removed separately from the tray.

A cross-sectional view of a slight modification of the structure is illustrated in Fig. 4. In this case the body of the box is designated 80 5^a, and the bottom 6^a is hinged thereto, as shown at 7^a, said bottom being provided with a pad 8^a. Partitions 9^a, located in the body, form stamp-receiving compartments. The body 5^a can be provided with a fabric or 85 other permeable bottom 10^a, constituting a top for the pad when the bottom 6^a of the box is closed. A cover 11^a is hinged, as shown at 12^a, to the upper portion of the body and constitutes a closure for the box. 90 In this structure the inking of the pad requires only the opening of the bottom 6^a and does not necessitate the removal of the stamps from the box.

95 It will thus be understood that a simple novel holder is provided wherein the stamps are supported directly on the inking means, so that they will be kept moistened and will be ready for use when removed from the box. The structure is simple, can be cheaply manufactured, and, moreover, can be made substantially dustproof.

100 From the foregoing it is thought that the construction, operation, and many advantages of the herein-described invention will 105 be apparent to those skilled in the art without further description, and it will be understood that various changes in the size, shape,

proportion, and minor details of construction may be resorted to without departing from the spirit or sacrificing any of the advantages of the invention.

5 Having thus described my invention, what I claim as new, and desire to secure by Letters Patent, is—

1. A stamp-holding box comprising a body having an inking-pad in its bottom, stamp-guides located over the pad and supported by said pad in the body, and a cover for the body.

2. A stamp-holding box having an inking-pad in its lower portion, and a stamp-receiving tray located in the box and supported upon and by the pad, said tray maintaining the stamps in engagement with the pad.

3. A stamp-holding box having an inking-pad in its lower portion, and a stamp-receiving tray located in the box and having a partition resting on the pad and forming stamp-receiving compartments, the inking-pad con-

stituting the bottom of said compartments.

4. A receptacle having side walls, and a bottom, an ink-pad located on the bottom, 25 and a stamp-holding tray located in the receptacle and having a bottom permeable to ink and resting on the top of the pad.

5. A receptacle having side walls, and a bottom, an ink-pad located on the bottom 30 and terminating short of the side walls, and a stamp-holding tray located in the receptacle and having a bottom permeable to ink and resting on the top of the pad, said tray having side walls, the lower portions of which extend between the lower ends of the pad and the receptacle-walls.

In testimony that I claim the foregoing as my own I have hereto affixed my signature in the presence of two witnesses.

PERCY STERNAU.
